UNITED STATES PATENT OFFICE.

THEODORE BIRKENMAIER, OF ST. LOUIS, MISSOURI, ASSIGNOR TO W. N. MATTHEWS AND BROTHER, INC., OF ST. LOUIS, MISSOURI, A CORPORATION OF NEW MEXICO.

SPRAY GUN.

Application filed July 11, 1921. Serial No. 428,312.

To all whom it may concern:

Be it known that I, THEODORE BIRKENMAIER, a citizen of the United States, residing at St. Louis, Missouri, have invented a certain new and useful Improvement in Spray Guns, of which the following is a full, clear, and exact description, such as will enable others skilled in the art to which it appertains to make and use the same, reference being had to the accompanying drawings, forming part of this specification.

Figure 1 is a side elevational view of my improved spray gun, partly in section.

Figure 2 is a vertical sectional view through the same showing the valve mechanism.

Figure 3 is a vertical sectional view through the spray head casting showing the trigger in rear elevation.

Figure 4 is a detail view of the floating valve operating saddle member.

Figure 5 is a detail view of the trigger.

This invention relates to a new and useful improvement in spray guns for use in spraying paint, powder and the like, the object being to construct a gun of this character which is simple and cheap in construction, one which can be easily repaired and cleaned, and which is not liable to get out of order.

My present invention is designed particularly as an improvement upon the spray guns of the type shown in the patent to Johns, No. 1,361,527 dated December 7, 1920 and patent to Heinrich, No. 1,382,641 dated June 28, 1921.

In the drawings, 1 indicates a casting in the form of a pistol having a handle portion 2 provided with an air conduit extending through a nipple 3 to which is connected a flexible tubing leading from a source of compressed air supply. 4 is a nipple by which paint, powder, or other material to be sprayed is introduced into the spray gun.

5 indicates a spray nozzle. 6 indicates a trigger member pivoted by means of a bolt 7 to a lug extending upwardly from the casting 1. This trigger is preferably made of stamped metal, the two leg portions thereof being connected together by a cross piece 6^a at the top overhanging portion of the trigger, while the lower ends of the legs are secured together by means of a rivet 8, the legs being bowed as shown in Figure 5 to embrace the casting 1 and the lower extremities

of said legs being provided with flanges 6^b extending in opposite directions to afford an extended area or surface against which the operator's finger may be placed in operation.

The casting 1 is provided with a trigger guard 1^a. 9 indicates a floating saddle member with which the upper overhanging end of the trigger 6 co-operates. This saddle member is provided with posts 10 which are received in openings 11 in casting 1, said openings preferably extending through the casting so that they may be readily cleaned in the event that paint or dirt becomes lodged therein, which might prevent the necessary freedom of movement of the saddle member 9.

12 indicates a valve seat screwed into the casting 1 and provided with a valve seat for co-operating with a valve 13 normally pressed upwardly against its seat by means of a spring 14.

15 indicates a floating extension of a valve stem which is preferably provided with a recess in its lower end to receive the upper end of the valve stem. Valve 13 controls the passage of air from conduit 16 to conduit 16^a leading to the nozzle 5. 17 indicates a plug screwed into casting 1, and which provides a seat for paint valve 18, said valve being normally held to its seat by means of a spring 19.

20 indicates a packing gland which receives an upwardly extending sleeve portion 17^a, being a continuation of the plug 17. This sleeve portion receives a valve stem 21 having a recess in its lower end to co-operate with the stem of valve 18. Valve 18 controls the passage of paint or the like entering through nipple 4 and passing through duct 22 to the nozzle 5.

In operation, nipple 3 is connected by a flexible tubing to a source of compressed air and nipple 4 is connected by suitable means to a source of paint (or other material) supply. When the trigger 6 is manipulated, the floating saddle 9 is depressed first operating and unseating valve 18 through the medium of the stem 21 so as to permit paint to be admitted to the nozzle 5. A continued rearward pull on the trigger will cause the saddle 9 to engage the shorter valve stem 15 which when depressed will unseat the valve 13 and permit air to flow through conduit 16^a to the nozzle 5.

The trigger is preferably made of a blank 110

stamped out of a single piece of metal, the forward upper portion of the overhanging end thereof being connected by the cross-piece 6^a. The valve stem extensions 15 and 21 are free to move in their openings and the saddle 9 is likewise free so that should these parts, which are exposed to the exterior stick and be prevented from operating, they can be removed from the gun with very little trouble, and cleaned and restored to place without dismantling the gun.

What I claim is:

1. In a spray gun, the combination of a valve stem and a pressed metal trigger for operating said stem, said trigger consisting of leg portions whose upper ends converge and are internally connected over the valve stem and whose lower ends are connected together by a fastening member and provided with extension flanges for affording a finger surface.
2. In a spray gun, the combination of a valve stem and a trigger for operating said valve stem, said trigger being made of a single blank integrally connected at its upper end bent to embrace a portion of the spray gun and having its lower extremities shaped to accommodate the operator's finger.
3. The combination of a spray gun, a trigger, a valve stem, and a floating independently movable member interposed between the valve stem and trigger.
4. The combination of a spray gun, a trigger, valve stems for operating valves in control of air pressure and paint or the like, respectively, and a floating independently

movable member interposed between said trigger and the ends of said valve.

5. In a spray gun, the combination of a casting formed with ducts for compressed air and paint, valves for controlling said ducts, stems on said valves, a trigger, and a floating member interposed between said trigger and said valve stems for sequentially operating the latter, said trigger co-operating with said floating member at a point between said valve stems.

6. In a spray gun, the combination of a casting having a paint duct, a valve for controlling said duct and a sectional valve stem co-operating with said valve, the outer section of which stem is removable from the exterior.

7. In a spray gun, the combination of a casting provided with air and paint ducts, valves for controlling said ducts, said valves having detachable stem extensions extending to the exterior and removable independently of the valves, and means for operating said valves through said detachable stem extensions.

8. In a spray gun, a casting having an air duct, a trigger, a valve stem, a saddle interposed between said trigger and said valve stem, and guiding posts on said saddle mounted for movement in openings on opposite sides of said casting, said trigger co-operating with said saddle at a point between said posts.

In testimony whereof I hereunto affix my signature this 15th day of June, 1921.

THEODORE BIRKENMAIER.
